PRINTING DEVICE FOR LUMBER

Henry H. Payzant, St. Paul, Minn., assignor to
 General Timber Service, Inc., St. Paul, Minn.,
 a corporation of Delaware

Application December 5, 1931, Serial No. 579,214

14 Claims. (Cl. 101—351)

It is an object of this invention to provide novel and efficient printing mechanism for printing on vertical surfaces of lumber.

A further object is to provide, in a machine of this kind, improved mechanism for uniformly distributing printing fluid on a rotary die, the device including mechanism for accurately adjusting the quantity or rate of supply of printing fluid to the die.

Another object is to provide, in a device of this kind, driving mechanism operable in timed relation to a lumber conveyor whereby proper placing of the impression on the lumber is insured.

A still further object is to provide driving connections between the lumber conveyor and printing mechanism which are adjustable to adapt the device to print uniformly on predetermined portions of the surfaces to be marked where the sizes or dimensions of the several pieces of lumber to be marked vary.

The invention also includes certain other novel features of construction which will be more fully pointed out in the following specification and claims.

Referring to the accompanying drawings:

Figure 1 is a front elevation of my improved printing device mounted on a lumber conveyor with a portion of the conveyor illustrated in section;

Fig. 2 is a side elevation of the device, as seen from the right of Fig. 1, and showing the adjacent portion of the lumber support and conveyor;

Fig. 3 is a plan view of the device with the casing cover or cap removed;

Fig. 4 is a vertical section taken on the line 4—4 of Fig. 3;

Fig. 5 is a fragmentary section taken on the line 5—5 of Fig. 4;

Fig. 6 is a vertical section taken on the line 6—6 of Fig. 3;

Fig. 7 is a fragmentary vertical section taken on the line 7—7 of Fig. 3;

Fig. 8 is a fragmentary section taken on the line 8—8 of Fig. 3;

Fig. 9 is a fragmentary vertical section taken on the line 9—9 of Fig. 6;

Fig. 10 is a fragmentary elevation showing details of the scraper adjustment with the notched handle removed to show parts otherwise concealed;

Fig. 11 is a detail, vertical section through the composition roller and support therefor for feeding printing fluid from the vertical disk to the distributing rollers;

Fig. 12 is a side elevation showing the main inking roll and support;

Fig. 13 is a detail showing one of the distributing rollers and support; and

Fig. 14 is a section taken on the line 14—14 of Fig. 1.

The device has a printing head 1 carrying a die 2 on its cylindrical periphery. The head 1 is removably secured to a vertical shaft 3, provided with anti-friction bearings 4 in a supporting casting 5. A long hub 6 on the head 1 projects upward along the shaft 3 and has rigidly fixed on its upper end a gear 7. Pivoted on a pin 8 in a suitable recess in the upper end of the shaft 3 is a pair of dogs 9. These dogs are normally thrust apart into engagement with the gear 7 by a small coiled spring 10. Driving connection between the shaft 3 and head 1 is established by a suitable key 1a (Fig. 4). By this arrangement, to permit removal of the head 1 and gear 7 from the shaft 3, it is only necessary to compress the spring 10 while moving the dogs 9 inward out of engagement with the upper surface of the gear.

As best shown in Figs. 1 and 2, the periphery of the head 1 projects at one side from a casing 11 through an opening 12 and the periphery of the gear 7 above the projecting portion of the head 1 is contained in a small projecting portion 11a of the casing 11. Pieces of lumber 13 to be marked are advanced along suitable supports 14 or skids 14 by a conveyor of well-known type. One suitable arrangement of conveyor and holding devices for the lumber is illustrated in the co-pending application of Henry H. Payzant, Serial Number 579,215, now Patent No. 1,966,396. Portions of a similar conveyor are illustrated in Figs. 1, 2 and 13 wherein a conveyor chain 15 is shown. This chain carries suitable lugs of well known construction for engaging the pieces of lumber 13 and is trained over driving sprocket 16 wheels, like the wheel 16, fixed on a power-driven shaft 17. A sprocket wheel 18 is revoluble on the shaft 17 and adjacent to the face of this sprocket wheel 18 is mounted a toothed segment 19 which is keyed to the shaft 17. A bolt 20 is pivotally supported on the sprocket wheel 18 and adapted to be placed in engagement with the segment 19 between any selected pairs of teeth thereon. The adjustment thus afforded makes it possible to change the angular position 25 of the wheel 18 relative to the shaft 17 driving the chain 15, with the result that the timing of the printing mechanism may be changed to adjust the position of the impression on the ends of pieces of lumber of different widths.

My improved printing mechanism is driven by a chain 21 trained on the sprocket wheel 18 and arranged to drive a small sprocket wheel 22 fixed on a horizontal shaft 23. This shaft 23 has suitable bearings at opposite sides of a casing 24 within which a beveled pinion 25 is keyed to the shaft 23. The pinion 25 drives a large beveled gear 26 (Figs. 6 and 9) and, meshing with the gear 26, is a beveled pinion 27 secured to the lower end of the vertical shaft 3 for driving the printing head 1. The gear 26 is fixed on a horizontal shaft 28 which is supported in a projecting bearing 29 and carries on its end, outside of the casing 24, a small sprocket wheel 30. As best shown in Fig. 2, a sprocket chain 31 is trained on the sprocket wheel 30 and arranged to drive a cam holder or disk 32 having a suitable toothed periphery to engage said chain. This cam disk 32 is keyed to a horizontal shaft 33 having bearings supported on opposite walls of a reservoir 35 for ink or other printing fluid. Fast on the shaft 33 within the reservoir 35 is an ink supply disk 36 having a conical back face 37 and a flat, vertical front face 38 from which the printing fluid is fed. The printing fluid is normally retained at about the level indicated by the dotted line 39 in Fig. 6.

From the upper periphery of the disk 36, the printing fluid is fed by a composition roller 40 arranged to intermittently engage the vertical face 38 of said disk. Details of the support for the roller 40 are shown in Fig. 11. A vertical shaft 41 has the roller 40 secured to its lower end and is freely journaled in anti-friction bearings carried by a pair of arms 42. These arms are pivotally supported on a vertical pin 43 (Figs. 3, 5 and 6). To actuate the roller 40 from a position in contact with the disk 36 to a position in contact with a distributing roller 44 and out of contact with the disk 36, a rod 45 is secured at one end to ears 46 integral with the arms 42 and at its other end carries mechanism to be actuated by a series of cam elements 47 secured to the face of the cam disk 32 (Figs. 2 and 7). The rod 45 passes freely through perforations in upstanding flanges integral with the arms 48 and 49. A collar 50 is fixed on the rod 45 at one side of a flange 51 on the arm 49, and a spring 52 is confined on said rod to engage the opposite side of the flange 51, suitable nuts 53 being threaded on the extremity of the rod to adjust the compression of the spring. The arm 49 carries a roller 54 to engage the back face of the disk 32 and the arm 48 carries a roller 55 to engage the cam elements 47 and front face of said disk. Connecting the arms 48 and 49 together, is a coiled spring 56. One end of the spring 56 is secured to an adjusting screw 57 having suitable lock nuts forming an abutment for the arm 49.

By this arrangement, the rollers 54 and 55 are held in contact with opposite faces of the cam disk 32 and separation of said arms against the action of the spring is permitted when the roller 55 is actuated by one of the cam elements 47. As the disk 32 rotates the cam elements 47 successively actuate the roller 55 and arm 49 to draw the rod 45 in such direction as to move the roller 40 into contact with the front face 38 of the disk 36. Upon movement of the cam elements 47 out of contact with the roller 55, the spring 56 actuates the rod 45 (through the connections therewith) to move the roller 40 out of contact with the face 37 and into contact with

the distributing roller 44, as indicated in Figs. 3 and 5.

As shown in Figs. 2 and 7, each of the cam elements 46 consists of a short, arcuate plate removably secured to the face of the disk 32 which is formed with a circular groove to receive said plates. The groove is concentric with the shaft 33 and a clamp ring 58 is arranged to overlap the several cam elements and removably hold them in place. The ring 58 is held in contact with the cam elements by suitable screws 59. A wide range of adjustment of the frequency of oscillations imparted to the roller 40 is obtainable by this arrangement of the cam elements 47, as it will be evident that the number and angular positions of the elements may be varied at will. Shorter or longer elements may be substituted for those illustrated if further variation is desired.

To convey the printing fluid from the roller 44 to the die 2 on the head 1, a large composition roll 60 is disposed in contact with said roller and die. As best shown in Figs. 4, 5 and 12, the composition roller 60 is secured to the lower end of a vertical shaft 61 and said shaft is provided with anti-friction bearings supported in a pair of arms 62. These arms are rigidly connected together and have a vertical pivot support consisting of a large pin 63 fixed at its base, as best shown in Fig. 6, in a boss 64 and having a bearing 65 projecting from the main casing wall. Ears 66 project from opposite sides of a hub connecting the arms 62 and these ears are bolted to similar ears formed on a hub 67 integral with an arm 68. This arm has attached to its otherwise free end a rod 69 (Figs. 4 and 6) which projects from the casing 5 and carries a spring 70 to thrust the composition roll 60 against the printing head. This spring 70 is normally retained under compression on the rod 69 and has an adjustable abutment for one end consisting of an externally threaded tube 71. The tube 71 is threaded in the casing 5 and the rod 69 is slideable in a suitable bearing in the outer end of said tube. To limit inward movement of the rod 69, as in case the head 1 is removed, suitable lock nuts are threaded on the outer end of said rod.

Composition rollers 73, 74, 75 and 76, of different diameters are disposed in contact with the periphery of the roll 60 to properly distribute the printing fluid thereon. As shown in detail in Fig. 13, each of these distributing rollers is mounted on the lower end of a vertical shaft having bearings in a support formed with a pair of projecting ears 77. Each pair of ears 77 is pivotally connected to the arms 62. The ears 77 for supporting the rollers 44, 73 and 74 are pivotally connected to extensions 78 on the arm 62. Small coiled springs 79 connect the several bearings for the rollers 44, 73, 74, 75 and 76 to the central bearing for the vertical shaft 61 so as to retain said rollers in resilient contact with the periphery of the roll 60. As shown in Figs. 3 and 6, small pinions 80 are disposed in mesh with a gear 81 fixed at the upper end of the shaft 61 to drive the several rollers 44, 73, 74, 75 and 76. These pinions 80 have different pitch diameters to correspond with the diameters of the several rollers driven thereby. The gear 81 is driven by the gear 7 secured to the shaft 3.

To limit the thickness of the film of printing fluid on the face of the disk 36, scraper blades 82 and 83 are provided (see Figs. 3, 6 and 8). The blade 82 is disposed to make con-

tact with the conical face 37 of the disk and the blade 83 is mounted adjacent to the vertical face 38 of said disk. To support the blades 82 and 83, a substantially horizontal plate 84 projects in 5 through an opening 85 in a wall of the casing. This plate 85 is integral with a plate 86 bolted to the outer surface of the casing. The inner end of the plate 84 is bifurcated, as shown in Figs. 3 and 6, and upon the upper surface of said 10 plate are formed guideways 87 and 88 for the plates 82 and 83 respectively. These guideways extend obliquely to the faces 37 and 38 of the disk 36 and the blades 82 and 83 are formed to slidably engage said guideways. To confine the 15 blades on the supports, screws 89 and 90 are threaded in the plate 84 and extend in slots 91 in the blades. The blade 83 may be actuated along the guideway 87 by a screw 92 having a handle 93 outside of the casing. The screw 92 is threaded in a suitable tapped hole in the 20 plate 86 and its inner end is arranged to revolvably engage the blade 83 in a T-shaped slot formed in said blade. The periphery of the handle 93 has a series of notches therein to 25 receive a spring-pressed detent 94. As best shown in Figs. 3 and 10, the detent 94 is pivoted on a pin 95 having a pair of spaced bearings 96 integral with the plate 86. A spring 97 is confined on a small bolt 98, extending through a 30 perforation in the detent 94, and is held under compression to urge the detent against the handle 93 by a wing nut 99 threaded on an end of the bolt 98. The opposite end of the bolt 98 is secured to the bearings 96 by a pivot pin 100. 35 By this arrangement, the detent 94 may be moved out of engagement with the periphery of the handle 93, by manipulation against the action of the spring 97, when it is desired to change the adjustment of the blade 83.

40 In use, the blade 82 is secured in proper adjusted position by tightening the screw 90. The blade 83, however, is left free for movement along the guide 87 by suitable adjustment of the screw 89 in the slot 91. This permits movement of 45 the blade 83 under the action of the screw 92 and any desired thickness of film of ink on the disk 36 is obtainable from the exterior of the casing by suitable manipulation of the handle 93 and detent 94.

50 In operation the shaft 17 is driven by a motor through suitable connections (not shown) to drive the lumber conveyor chain 15 and sprocket wheel 18 for actuating the printing mechanism in timed relation to each other. Pieces 55 of lumber 13 are advanced along the skids 14 by the lugs on the chains 15 in such position that the end of each piece is brought in contact with the rotating die 2 on the printing head 1. Suitable mechanism, such as that described 60 in the copending application for Lumber marking machines, of even date herewith, is employed to retain the pieces of lumber against movement out of contact with the die during the printing operation. The spacing of the lugs on 65 the chains 15 has a fixed relation to the spacing of the dies on the head 1 so that the impression is placed in uniform position on the end of each piece of lumber. Proper placing of the impression is secured by adjustment of the 70 bolt 20 in engagement with the teeth on the segment 19. Thus the impression may be placed centrally, or otherwise, as desired, on the ends or sides of boards of different widths as they are conveyed rapidly along a substantially horizontal support.

Having described my invention, what I claim as new and desire to protect by Letters Patent is:

1. A printing device for lumber having in combination a rotary head arranged to print on a substantially vertical surface of lumber, a reservoir, a disk arranged to be partially submerged in printing fluid in said reservoir, an inking roll in contact with the periphery of said head, a plurality of distributing rollers of different diameters engaging the periphery of said inking roll, means for positively rotating said rollers and roll in timed relation to said head and means for transmitting printing fluid from said disk to said roll. 5

2. A printing device for lumber having in combination a printing head revoluble about a vertical axis to print on a substantially vertical surface of lumber, a reservoir, a disk arranged to be partially submerged in printing fluid in said reservoir, an inking roll in contact with said head, 15 a plurality of distributing rollers engaging the periphery of said inking roll, means for positively rotating said rollers and roll in timed relation to said head and means for transmitting printing fluid from said disk to said roll. 20

3. A printing device for lumber having in combination a rotary printing head arranged to print on a substantially vertical surface of lumber, a reservoir, a disk arranged to be partially submerged in printing fluid in said reservoir, an inking roll mounted above said reservoir in contact with the periphery of said head, a plurality of distributing rollers engaging the periphery of said inking roll, a train of gears mounted above said head, roll and rollers for positively rotat- 35 ing said rollers and roll in timed relation to said head and means for transmitting printing fluid from said disk to said roll.

4. A printing device for lumber having in combination a vertical drive shaft, a printing head 40 removably secured to said shaft, a gear rigidly secured to said head above the same on said shaft, an inking roll revolvably mounted in engagement with the periphery of said head, a series of distributing rollers engaging the periphery of said 45 inking roll and a series of gears severally connected to said rollers and roll for rotating the same, one of the gears of said series being in mesh with said first mentioned gear to establish driving connection therewith. 50

5. A printing device for lumber having in combination a vertical shaft, a printing head secured to said shaft, a gear secured to said head, a series of distributing rollers for printing fluid, an arm, bearings for said distributing rollers sup- 55 ported on said arm, gearing for positively actuating said rollers carried by said arm, a pivotal support for said arm, a spring for actuating said arm toward said head to retain one of said rollers in contact with said head and for retaining 60 said gearing in driving connection with said first mentioned gear and means for adjusting the tension of said spring.

6. A printing device for lumber having in combination a rotary printing head, a roll for supply- 65 ing printing fluid to the periphery of said head, an arm movably supporting said roll, a pivotal support for said arm, a series of distributing rollers of different diameters, means movably supporting said rollers on said arm, resilient means 70 for retaining said rollers in contact with said roll and resilient means for retaining said roll in contact with said head.

7. A printing device for lumber having in combination a rotary printing head, a roll for sup- 75

- plying printing fluid to the periphery of said head, an arm movably supporting said roll, a pivotal support for said arm, a series of distributing rollers, means movably supporting said rollers.
- 5 5. on said arm, means for retaining said rollers in contact with said roll, means for actuating said arm to move said roll into contact with said head and driving connections between said roll and rollers.
- 10 10. A printing device having in combination a printing head, a reservoir for printing fluid, a horizontal shaft, a disk fixed on said shaft and adapted to be partially submerged in printing fluid in said reservoir, a fluid feed roller, a support for said roller permitting movement of the same to and out of contact with said disk, means for delivering the printing fluid from said roller to said head and means for actuating said roller comprising a cam wheel secured to said shaft.
- 15 15. a plurality of separate cam segments removably secured to a vertical face of said cam wheel, power driven means for rotating said shaft, means for securing said cam segments in selected, angular positions on said cam wheel independently of 20 each other and connections secured to said support for said roller and movable by said cam segments to actuate said support and roller.
9. A printing device having in combination a printing head, a rotary disk arranged to be partially submerged in printing fluid, a fluid feed roller, a support for said roller permitting movement of the same to and from contact with said rotary disk, means for delivering printing fluid from said roller to said head and means for 25 actuating said roller comprising a revoluble cam wheel mounted in spaced parallel relation to said disk, a plurality of independently removable cam segments mounted on said wheel, means for securing said cam segments in selected, different, angular positions on said wheel independently of each other, power driven means for rotating said disk and wheel, a second roller arranged to be actuated by said cam segments and connections between said second roller and first 30 mentioned roller support.
- 40 10. A printing device having in combination a printing head, a rotary member arranged to receive a coating of printing fluid, a fluid feed roller, a support for said roller permitting movement of the same to and from contact with said rotary member, means for delivering the printing fluid from said roller to said head and means for actuating said roller comprising, a cam shaft, a disk secured to said shaft, a ring mounted on 35 a face of said disk, a plurality of cam members adapted to be frictionally engaged by said ring to removably secure them to said disk, means for clamping said ring in engagement with said cam members to secure them in selected different angular positions on said disk, means for rotating said shaft, and connections secured to said support for said feed roller and movable by said cam members successively to actuate said support for said feed roller.
- 5 11. A printing device having in combination a printing head, a rotary member arranged to receive a coating of printing fluid, a fluid feed roller, a support for said roller permitting movement of the same to and from contact with said rotary member, means for delivering printing fluid from said roller to said head and means for 10 actuating said roller comprising a revoluble disk, a plurality of cam members mounted on a face of said disk, means for rotating said disk, arms pivotally supported near opposite faces of said disk, rollers carried by said arms to contact with opposite faces of said disk respectively, one of said last mentioned rollers being in position to be actuated by said cam members, a spring connecting said arms to retain said roller in contact with said disk, and a rod connecting said 15 support for said first mentioned roller to one of said arms.
12. A printing device having in combination a reservoir for printing fluid, a disk adapted to be partially submerged in printing fluid in said reservoir, a scraper blade arranged to engage a face of said disk, a guide for said blade extending obliquely toward said face, said blade being movably obliquely toward said face on said guide and means for securing said blade in adjusted positions on said guide.
13. A printing device having in combination a reservoir for printing fluid, a disk adapted to be partially submerged in printing fluid in said reservoir, a scraper blade adjacent to a face of said disk, a guide for said blade extending at an acute angle to the face of said disk and adjusting means extending out through the wall of said reservoir for actuating said blade along said guide.
14. A printing device having in combination a 45 reservoir for printing fluid, a disk adapted to be partially submerged in printing fluid in said reservoir, said disk having flat and conical faces respectively, scraper blades arranged adjacent to said faces respectively, guides for said blades arranged to permit movement of the blades obliquely toward said faces respectively and means for securing said blades in adjusted positions on said guides.

HENRY H. PAYZANT. 55
